ABSTRACT: A clip for the retention of a web wound upon a reel having a flange with radially extending slot for slidable movement of the clip along the flange. The clip includes a pressure bearing means having the general shape of a frustum of a wedge. This permits first contact to be made at the thick end of the wedge and through resilient cantilevered action, web contact along the length of the pressure bearing means is ensured. The clip has gripping means which includes a friction fit of the flange width. The gripping means also includes a pair of resilient shoulders which cooperate with the thin end of the wedge for gripping the flange to maintain the position of the clip on the flange. Gripping action and web retention are further enhanced by having a neck portion resiliently couple the pressure bearing means with the gripping means.

WEB RETENTION CLIP

BACKGROUND OF THE INVENTION

This invention relates to clips for the retention of a web wound upon a web storage device. More particularly, this invention relates to clips which are moveable along a flange of a reel having a radial extending slot for guiding and positioning the clip directly above and contiguous with an outer lap of a wound web to prevent the unwinding of the web from the reel.

In the prior art, clips of this type are known to include a flat surface pressure bearing means for placing pressure on the outer lap of a web and a neck portion for slidable movement in the slot to maintain a friction fit with the slot to limit movement of the clip. The problem with these prior art clips, an example of which is illustrated in French Pat. No. 1,235,625, is that when placed on a reel firmly against a roll of film, the forces lift the pressure bearing means and cause it to rotate about the edge of the film nearest to the flange with the slot. Thus, the only contact with the outer lap of film is just at points along the edge of the film or there is no contact at all.

Another problem with these prior art clips is that the use of a friction fit between slot and neck portion is insufficient to prevent the clip from loosening and sliding up the slot and off the film. In addition, the use of spaced parallel plate like elements for gripping each side of the flange with a friction fit in combination with the aforementioned neck portion is also insufficient for providing proper gripping action. Both of these grippers are highly reliant on close dimensional tolerances and to maintain the necessary quality control would defeat the great need for an inexpensive clip. Furthermore, in positioning such a clip on a reel, the inner plate member may have to be forced past the film and may do damage to the web material.

In order to overcome these problems one may use resilient pads on the pressure bearing means and on the grippers. This modification will successfully eliminate the tolerance problems and perhaps also will maintain some pressure over a sufficient film width, but considerable additional costs will be added in the manufacture of these clips.

Another proposed solution is to have a rounded pressure bearing means and a rounded gripper plate. With regard to the former, this may ensure contact with the film but the entire force will be concentrated at the point of contact which could distort the film. Also, this minimal contact may not be sufficient to prevent the film from vibrating loose and unwinding. With regard to the latter, the rounded gripper is also subject to tolerance problems since an insufficient frictional fit will permit the clip to ride up the flange.

SUMMARY OF THE INVENTION

It is an object of this invention to provide an improved web retention clip adapted to be slidably moved along a flange of a web storage device having a slot for guiding the clip so that the clip may apply pressure to a web wound on the device to prevent the unwinding of the web from the device.

It is another object of this invention to provide an inexpensive web retention clip which insures a greater degree of contact of the web by the clip.

It is still a further object of this invention to provide an inexpensive web retention clip with improved web retention means and which maintains the position of the clip on a web storage device and substantially prevents the clip from riding up the device and off the web.

The clip comprises a cantilevered pressure bearing means including a web contacting portion to prevent a web from unwinding from a storage device. The clip is so formed that the pressure bearing means is permitted to resiliently rotate upon contact with the web to allow contact of the web by the entire web contacting portion. The clip includes a support with holding means for maintaining the position of the clip on the device wherein the support is resiliently coupled to the pressure bearing means for enhanced web retention and gripping of the storage device.

BRIEF DESCRIPTION OF THE DRAWING

The invention and its objects may be more fully understood from the following description, when it is read with reference to the accompanying drawing in which:

FIG. 1 is a longitudinal side view of one embodiment of the present invention.

FIG. 2 is a top view of the embodiment illustrated in FIG. 1.

FIG. 3 is a perspective view of the clip shown in FIG. 1.

FIG. 4 is a top view of the clip shown in FIG. 1 in its in-use position.

FIG. 5 is a longitudinal cross-sectional view on the line 5—5 of the clip shown in FIG. 4.

DESCRIPTION OF THE PREFERRED EMBODIMENT

In the preferred form of the invention and with particular reference to FIGS. 1-3, the novel device may take the form of a clip 11 having a cantilevered pressure bearing means 12 which has the general configuration of a frustum of a wedge with a thick end 13 and thin end 14. The clip is completely formed by the molding of a plastic material such as polypropylene, polyurethane or polyethylene, etc. Material costs may be reduced by employing oppositely disposed recessed faces 17 and 15 with relatively raised peripheral portions 16 and 16' respectively. In addition to reducing the cost, increased strength and stiffness is achieved since the pressure bearing means has an I-beam like cross section in both the longitudinal and transverse directions. Connected to and contiguous with end 14 of the pressure bearing means is a neck portion 18 adapted to be slidably moved in a slot of a reel. Also connected to the neck portion is a cantilever support member 19 which includes a depending portion 25 which functions as a handle. Member 19 further includes an inner surface 42 and two resilient shoulders 23 and 24 disposed on either side of neck portion 18. With reference to FIG. 2, it can be seen that the inner surface of each of these shoulders begins at 26 and 27 respectively and extends in a lateral direction from the neck portion. The shoulders may be parallel to or slightly sloped away from pressure bearing means end 14 and have their respective ends 21 and 20 turned in toward end 14. The ends 20, 21 are spaced from end 14 at a distance less than the thickness of the reel flange upon which the clip is placed. A tapered buttress 43 extends from each of the ends 20, 21 toward depending portion 25. A raised guide rib 22, centrally disposed on the inside of support member 19, runs from the lowest point of member 19 up until it joins with neck portion 18. The neck portion 18 and rib 22 are formed such that they have approximately the same width.

50

OPERATION

When in use, and with particular reference to FIGS. 4 and 5, the clip is positioned on a reel 30 having hub 40, flanges 38, 39 and a web 31, such as film or tape, wound therebetween. Guide rib 22 cooperates with inner surface 42 and depending portion 25 to facilitate ease of positioning the clip in radial slot 34 of reel 30. Rib 22 and neck portion 18 are located in slot 34 and clip 11 is guided radially toward the outer lap 32 of web 31. Guide rib 22 moves within the slot and cooperates with the neck portion to maintain the clip in an upright position. The web-contacting portion of the pressure bearing means 12 is the raised peripheral portion 16 although it should be appreciated that the clip may be made without a recess 17, in which case the web-contacting portion will be the full lower surface of the means 12. The points on the raised periphery 16 define a plane which is positioned between flanges 38, 39 of reel 30. Because of the wedge-shaped configuration of means 12, the plane slopes away from the inner surface of flange 39 and is inclined downwardly towards the hub 40 so that the peripheral portion 16 associated with end 13 will be the first to make contact with the web. As the clip is forced farther radially along the slot the pressure bearing means 12 is caused to resiliently rotate about the juncture of neck portion 18 and rib 22 so that contact with the outer lap 32 is made by the entire

75

web-contacting portion 16. For best results, rotation will occur when the neck portion 18 will be entirely radially outward of the web portion to be contacted. This permits placement of the clip on the flange without the necessity for any portion of the clip having to be inserted between the web edge and the inner surface of flange 38. It also permits resilient coupling between means 12 and support 19, which permits increased pressure to be exerted on the web. The resilient rotation of means 12 has the advantage that the web contacting portion is continuously applying a force on the web since the pressure bearing means tends to return to the unstressed state. The force which is distributed over the web area contacted by the contacting portion 16 results in sufficient pressure on the outer lap to prevent it from vibrating loose and unwinding.

It will be appreciated that the clip has further increased web retention capabilities because it is formed with high stiffness in the neck portion 18. The stiffness results from designing the clip with a relatively narrow neck width, as shown vertically in FIG. 2, in relation to its depth, as shown vertically in FIG. 1. Since the neck width is made quite narrow and is even more narrow than it is deep, resilient rotation about the narrow neck will require a relatively high force but in return this results in a correspondingly high force being exerted on the web by the pressure bearing means. In addition, the I-beam cross section of the means 12 also increases the stiffness of the cantilever and results in increased pressure on the web.

To prevent the forces of the web on the portion 16 from forcing the clip to slide up the flange and off the web the clip is provided with gripping means which maintain the connection between the pressure bearing means 12 and the support member 19 in a stressed state. One gripping means used includes a friction fit with the inner and outer surfaces of the flange by end 14 of the pressure bearing means and shoulder parts 26 and 27. A friction fit with the slot 34 by the neck portion 18 may also be used but is not necessary. Further gripping action is achieved along the turned in portions 20 and 21 which strongly resiliently press against the outside of the flange. This is because the shoulders 23, 24 are flexed away from the flange about an axis parallel to rib 22 when the clip is placed on the reel and the resiliency of the plastic tends to return the shoulders to their unstressed state. The ends 20, 21 are strengthened by tapered buttress 43 which provides a camming action when the clip is placed on the reel so that it gently leads ends 20, 21 over the top edge of flange 38. A viselike gripping action is achieved by the top edge of end 14 resiliently turning toward shoulder portions 26, 27 during rotation of pressure bearing means 12 to further enhance the friction fit.

Still other gripping action is achieved as a result of the resilient coupling of the cantilevered pressure bearing means 12 to support member 19. With reference to FIG. 5 the clockwise rotation of the means 12 forces portions of member 19 to tend to rotate in the same direction and, being prevented by the outer surface of the reel flange from doing this, a greater force is applied to the flange by the gripping members

associated with support member 19. In addition to gripping members 20-21 and 26-27, the lower portion of inner surface 42 adjacent rib 22 is also forced up against the flange to frictionally engage same. Thus, it can be appreciated that the frictional engagement between clip and reel is enhanced by the resilient coupling between pressure bearing means 12 and support 19.

The invention has been described in detail with particular reference to preferred embodiments thereof, but it will be understood that variations and modifications can be effected within the spirit and scope of the invention.

I Claim:

1. A clip for the retention of a web upon a web storage device having a hub and at least one flange extending radially therefrom, said flange being provided with a radially extending slot for slidably supporting said clip, said clip comprising:
20 support means positionable adjacent one side of said flange and including means for frictionally engaging said one side to maintain the position of said clip on said reel; pressure bearing means for exerting pressure on said web and positionable adjacent the opposite side of said flange to extend in cantilevered fashion and in overlying relationship relative to said hub;
25 a neck portion connecting and resiliently coupling said support and said pressure bearing means to enhance the pressure exerted on said web and the frictional engagement of said flange, said neck being of such size as to be slidably positionable in said slot; and
30 a web contacting portion on said pressure bearing means, said web contacting portion being positionable radially outward of said hub such that all points in said web contacting portion are in a plane which slopes away from said opposite side of said flange at an inclined angle toward said hub, so that when placing said clip on said flange an end of said web contacting portion farthest from said support means will be the first to contact a portion of said web and by resilient rotation of said pressure bearing means the entire web contacting portion may contact said web, and said neck portion being so related to said web contacting portion and said support means that said neck will be entirely radially outward of said web portion.
35 2. The invention according to claim 1 wherein said pressure bearing means has the general configuration of a frustum of a wedge.
40 3. The invention according to claim 2 wherein said pressure bearing means includes two oppositely directed recessed faces and said faces being at least partially bounded by a relatively raised periphery.
45 4. The invention as defined in claim 3 wherein said periphery of at least one of said faces comprises said web contacting portion.
50 5. The invention according to claim 1 wherein said support means includes resilient shoulders which have ends turned in toward said pressure bearing means for gripping said one side of said flange.
